DESIGN FOR A CABINET FOR A CHLORINATOR

Roy Blair Everson, Chicago, Ill.

Application April 5, 1937, Serial No. 68,559

Term of patent 14 years

To all whom it may concern:

Be it known that I, Roy Blair Everson, a citizen of the United States and a resident of the city of Chicago, county of Cook, State of Illinois, have invented a new, original, and ornamental Design for a Cabinet for a Chlorinator, of which the following is a specification, reference being made to the accompanying drawing forming a part thereof, which illustrates in perspective a cabinet for a chlorinator embodying my design, the characteristic feature thereof being the chlorinator shown in full lines.

I claim—

The ornamental design for a cabinet for a chlorinator, substantially as shown, and described.

ROY BLAIR EVERSON.
